[57] CLAIM

The ornamental design for a can carrier, substantially as shown and described.

DESCRIPTION

FIG. 1 is a top plan view of a can carrier showing our new design, the bottom being the same in appearance; FIG. 2 is an elevational view, the opposite side being the same in appearance; and

FIG. 3 is a view looking from the right of FIG. 2, the opposite side being the same in appearance.

*Fig. 1.**Fig. 2.**Fig. 3.*
